DESIGN FOR A FINGER RING

Abraham G. Sager, Chicago, Ill.

Application June 22, 1948, Serial No. 147,130

Term of patent 14 years:

(Cl. D45—10)

To all whom it may concern:

Be it known that I, Abraham G. Sager, a citizen of the United States and resident of Chicago, in the county of Cook and State of Illinois, have invented a new, original, and ornamental Design for a Finger Ring, of which the following is a specification, reference being had to the accompanying drawing, forming a part thereof.

In the drawing,

Figure 1 is a perspective view of a finger ring, showing my new design;

Figure 2 is a side elevation of the ring shown in Figure 1.

I claim:

The ornamental design for a finger ring, as shown.

A. G. SAGER.
